UNITED STATES PATENT OFFICE

123,269

DESIGN FOR A TOY BARROW

William Longstreet, Cleveland, Ohio

Application March 7, 1940, Serial No. 90,749

Term of patent 3½ years

To all whom it may concern:

Be it known that I, William Longstreet, a citizen of the United States, residing in the city of Cleveland, county of Cuyahoga, and State of Ohio, have invented a new, original, and ornamental Design for a Toy Barrow, of which the following is a specification, reference being had to the accompanying drawing, forming a part thereof:

I claim:

The ornamental design for a toy barrow, substantially as shown.

WILLIAM LONGSTREET.
